2 Claims. (Cl. 307—141.4)

This invention relates to selector switches of the ratchet operated kind such as are used as single-motion or two-motion selectors in automatic telephone exchange systems and elsewhere.

Basically a ratchet switch includes an electromagnetically operated ratchet and pawl mechanism which moves the switch one step forward for each energization (or de-energization) of an electromagnet energizing coil of the switch. In order to give the ratchet switch a self-drive action, requiring alternate energization and de-energization of the operating coil, the switch is also commonly provided with interrupter contacts which are connected in the energizing circuit for the coil and on energization of the coil are opened to break the energizing circuit. The consequent de-energization of the coil results in re-closure of the interrupter contacts, with consequent re-energization of the coil provided that the energizing circuit remains otherwise complete. The interrupter contacts have the disadvantage of requiring careful adjustment and of being liable, due to wear, to give trouble or at least to require increased maintenance attention.

According to the invention the interrupter contacts of a ratchet selector switch are replaced, in a stepping circuit for the switch, by a transistor which has the energizing coil of the switch magnet connected in its collector-emitter circuit and which is connected as a blocking oscillator by virtue of a regenerative feedback coupling provided between its collector-emitter circuit and its base circuit. Preferably the regenerative coupling is provided by means of a feedback coil magnetically coupled with the energizing coil of the switch.

The invention may be better understood by consideration of the accompanying drawing the single figure of which illustrates for a single-motion ratchet switch a stepping circuit which permits the switch to be pulse-driven or effectively self-driven.

Referring to the drawing a ratchet switch RS is shown in conventional manner as having two contact banks A1 and A2 (of which A2 is a control bank) with associated wipers w1 and w2 which are driven by means of a ratchet and pawl mechanism (not shown) under control of an electromagnet DM. It is assumed that in order to step the wipers w1 and w2 by one step, the electromagnet DM requires to be energized and then de-energized. The electromagnet DM has two magnetically coupled coils c1 and c2 of which c1 is the energizing coil and c2 is a feedback coil. The energizing coil c1 is connected in the collector-emitter circuit of a transistor T and the feedback coil c2 is connected in the base circuit of the transistor between the base and a source of positive bias potential (+). The magnetic coupling between the coils c1 and c2 affords a regenerative feedback from the transistor emitter-collector circuit to its base circuit but the positive bias on the base normally prevents oscillatory action by preventing conduction of the transistor. A negative-going stepping pulse P applied to the base of the transistor T by way of a capacitance coupling network C, R and an appropriately poled rectifier Rf will tend to cause conduction of the transistor. Consequent current flow in the switch coil c1 initiates a regenerative action through the feedback coil c2. The current flow through the transistor therefore rapidly increases and the mag-

2

netic flux induced by the energizing coil c1 and linking the feedback coil c2 builds up to saturation. On reaching saturation the regenerative action ceases and the transistor becomes blocked off, that is non-conducting, until the flux has died away. Since the energizing coil c1 has now been energized and then deenergized again, the ratchet switch RS is therefore caused to step once.

If, instead of and as distinct from a stepping pulse P, a continuous negative direct current potential is applied to the transistor base over a base connection lead l, then a blocking oscillator action similar to that just described but continuously repeated can be obtained, thus imparting an effective self-driving action by which the switch is repeatedly stepped until the negative bias on lead l is removed. By arranging that this negative potential is applied from a control contact bank of the switch, constituting a testing or homing bank, a hunting or homing action can be obtained in a manner readily apparent to one skilled in the automatic telephone art. For example, in the drawing the base connection lead l is shown included in a base circuit (independent of that including the feedback coil c2) in which it is connected through a resistor R1 and starting contacts st to the wiper of control bank A2 of the switch RS, this arc being used as a marking bank.

The home contact h of the control bank A2 is connected to negative battery over normally-closed contact sh and the other contacts 1 . . . 0 of the bank are each selectively connected, by change-over switch m1 . . . m0, either to negative battery or to earth. On closure of contact st the negative potential appearing at contact h of control bank A2 starts the self-driving action already described, this action continuing as the wiper w2 passes over those contacts 1, 2, 3 . . . which also have a negative potential applied to them by their respective switches m1, m2, m3 . . . The self-drive action is stopped at the bank contact, e.g. contact 5, which has been marked by operation of the relevant switch (m5) to apply earth potential to that contact instead of the negative potential. A subsequent homing action can be achieved by a similar self-drive action initiated by restoring contact m5 and opening contact sh. These provisions for self-driving action may be made either instead of or in addition to the provisions for single-step operation.

Since the transistor can induce significant gain, the operation of the ratchet switch can be controlled from a low power source which may be switched electronically rather than mechanically or electromechanically, for instance by means of transistor binary pairs. Furthermore in the case of single-step operation, the stepping action can be effected by a short duration pulse P such as may be obtained from an electronic or ferrite core gate circuit. The stepping circuit is therefore specially suited to electronic control. It may also be observed that the path over which the operating signal, as constituted by the stepping pulse P or the negative bias on lead l as the case may be, is applied, includes neither the switch energizing coil nor the feedback coil. Since the operating signal path can therefore be non-inductive, it can if necessary be of considerable length and may be run in a cable without causing radiation or interference; moreover in deriving the bias for self-drive operation from a marking contact bank such as A2 of the switch, the wiper (w2) of this contact bank need not be a bridging wiper but can be of a non-bridging kind.

What I claim is:

1. In combination:
  - a source of continuous potential;
  - a ratchet operated selector switch including a plurality of contact banks each having a first contact and succeeding contacts at least one of which con-

- tacts is marked by the absence of said potential, said contact banks having thereon cooperating wipers, said contact banks including a control bank;
 a ratchet operating electromagnet for effecting actuation of said wipers, said electromagnet having an energizing coil therefor; 5
 a transistor blocking oscillator constituting a stepping circuit for said wipers and comprising a transistor having a collector-emitter circuit including said energizing coil, a base circuit including regenerative feedback means from said collector-emitter circuit, and a further independent base circuit including a base connection to the wiper of said control bank; 10
 and means for applying to said first contact when initially engaged by the wiper of the respective control bank and to said number of succeeding contacts therein said continuous potential from said source over said wiper and base connection to initiate conduction of the transistor and to effect a resultant sequence of blocking oscillator actions in said transistor blocking oscillator by which the electromagnet energizing coil is repeatedly energized with resultant stepping of the selector switch until the control bank wiper reaches said contact marked by the absence of 15
 said potential. 25
2. In combination:
- a source of continuous potential;
 a ratchet operated selector switch including a plurality of contact banks with cooperating wipers, said contact banks including a control bank, and in which 30
 said banks each have a first contact and succeeding contacts at least one of which is marked by the absence of said potential thereon;

- a ratchet operating electromagnet for effecting actuation of said wipers, said electromagnet having an energizing coil therefor and a further coil magnetically coupled with the energizing coil;
 a transistor blocking oscillator constituting a stepping circuit for said wipers and comprising a transistor having a collector-emitter circuit including said energizing coil, a base circuit including said further coil connected as a regenerative feedback means from said collector-emitter circuit, and a further independent base circuit including a base connection to the wiper of said control bank;
 and means for applying to said first contact when initially engaged by the wiper of the respective control bank and to said number of succeeding contacts therein said continuous potential from said source over said wiper and base connection to initiate conduction of the transistor and to effect a resultant sequence of blocking oscillator actions in said transistor blocking oscillator by which the electromagnet energizing coil is repeatedly energized with resultant stepping of the selector switch until the control bank wiper reaches said contact marked by the absence of 20
 said potential.
